UNITED STATES PATENT OFFICE.

CHARLEY W. ROBERSON, OF MINERAL SPRINGS, ARKANSAS.

MAIL-TRANSFERRING MECHANISM.

1,249,670.

Specification of Letters Patent. Patented Dec. 11, 1917.

Application filed July 30, 1917. Serial No. 183,541.

To all whom it may concern:

Be it known that I, CHARLEY W. ROBERSON, a citizen of the United States, residing at Mineral Springs, in the county of Howard 5 and State of Arkansas, have invented certain new and useful Improvements in a Mail-Transferring Mechanism, of which the following is a specification.

This invention relates to mail transferring 10 mechanism, and has for its primary object to generally simplify and improve the construction and operation of such devices, as well as to increase the efficiency thereof.

A further object of the invention is to 15 provide improved means for facilitating the interchange of mail bags between a moving train and a fixed element beside the track, which operates in such manner that a number 20 of mail bags may be interchanged at one and the same time without danger of the bags dropping to the ground or passing beneath of the wheels of the moving train, and of little likelihood of the bags becoming damaged or broken.

Still further objects reside in providing a 25 mechanism of the character set forth which shall be of simple and comparatively inexpensive construction, which performs the interchanging operation automatically, which 30 at all times protects the mail pouches from damage by rain or snow, which has its various movable parts so constructed and arranged as to minimize the opportunity for 35 wear, breakage or derangement, and which in use.

With these objects in view together with others which will appear as the description 40 proceeds, the invention resides in the novel formation, combination and arrangement of parts, all as will be described more fully hereinafter, illustrated in the drawings and particularly pointed out in the claims.

In the drawings:

Figure 1 is a fragmentary side elevation 45 of a railway car of conventional form, the said car being equipped with one of the bag holding and receiving members, and the view also illustrating a bag receiving and 50 holding member beside the track.

Fig. 2 is a sectional view looking through the members upon the car and beside the track, and illustrating the manner in which the said elements telescope during the bag 55 interchanging operation.

Fig. 3 is a detail perspective view of the

bag holding member which is adapted to be affixed to the side of the railway coach.

Fig. 4 is a similar view of the member supported beside the track, and 60

Figure 5 shows a mail pouch of that type which is adapted for use in containing the mail to be transferred with an apparatus of my invention.

Referring now to the drawings, 6 indicates a conventional form of railway car, and to which one of the members, hereinafter referred to as the movable member, is secured. The movable member comprises a substantially tubular shell or casing 7, 70 affixed so as to be disposed in horizontal position upon the side of the car and adjacent or across one of the doors therein. Blocks 8 are illustrated in the present instance for effecting the connection between the side of 75 the coach and the tubular member. The outer side of the tubular shell 7 is slotted throughout its length as indicated at 9.

The shell or casing is provided upon its inner side with a pair of doors 10, the said 80 doors being arcuate as shown so as to conform to the contour of the shell when closed, and each of these doors carries a mail bag supporting rod 11. These rods are secured to the doors at their inner ends, and the 85 opposite ends of the rods are unattached, the said rods being disposed outwardly in directions opposite to each other. The said rods are so arranged upon their respective doors that when the latter are swung to 90 closed position and held by the latches 12, the said rods will be spaced slightly from the inner walls of the casing, at the upper side thereof, and parallel with the axis of the said casing. Leaf springs 13 are 95 secured to the doors 10 remote from the point of connection of the rods 11 therewith, and these springs are yieldably engaged with the free ends of the said rods.

Extending across the casing 7 upon the 100 interior thereof and midway between the ends of the said casing is a stop, the said stop including a centrally disposed arm 14, and a pair of arcuate members 15. These members are spaced from the inner walls 105 of the casing and from each other.

The fixed member to be secured by the track is indicated at 16, and this member is of hollow cylindrical form, open at both ends, and the said member is adapted to 110 pass longitudinally through the movable member 7. The member 16 is suitably sup-

ported in horizontal position at one side upon a suitable bracket or support 17. The fixed member 16 is provided at its outer side with the longitudinally disposed slot 18, 5 and this slot is coextensive with the said member. This casing or fixed member 16 is also equipped upon its interior with a pair of longitudinally extending oppositely disposed bag supporting rods 19, the inner 10 ends of the said rods being secured to the casing 16, while the other ends thereof are free, while the said rods for the major portion of their length are spaced parallel with and slightly below the upper side of the casing. This fixed member 16 is also equipped 15 with a stop; the said stop being disposed between the adjacent ends of the rods 19, and comprises a centrally disposed arm 20 and the arcuate arms 21. It will be observed that 20 the points of connection of the arms 20—21, and of the arms 14—15 of the movable member, are relatively close together, being spaced apart a difference sufficient to permit 25 of the same being inclosed by the slots 18 and 9 of the fixed and movable members respectively.

The casing 16 is provided adjacent its inner side with longitudinally disposed slots 22, and these slots are arranged adjacent 30 and coextensive with the oppositely disposed rods 19. The ends of the slots 22 communicate with short arcuate slots 23, the arcuate slots being provided so as to facilitate the application of the mail bags to the 35 interior of casing.

The mail bags employed in connection with a transferring apparatus are indicated at 25, and each is provided at its upper end with a loop 24, the said loops being adapted 40 to engage over the rods 11 or 19 of the movable or fixed members. When a number of bags are suspended by the rods within the casing, the same may be held together by chains, such as that shown at 25'.

45 In practice, the fixed member is arranged beside the track in spaced parallel relation to the ground, and is elevated above the ground sufficiently to telescope with the member 7 arranged in a similar manner 50 upon the side of the car. It will be observed that the ends of the members 7 are flared so that the proper assembling of the telescoping members is assured. Assuming that the car be moving in the direction indicated 55 by the arrow in Fig. 1, mail bags to be delivered to the stationary member will be suspended from the loop 24 upon the rod 11 at the rear end of the casing 7. The pouches to be delivered to the casing upon the train 60 will be suspended from the rods 19 to the left of the casing 16, as shown in the said figure. As the car advances, the casing 7 passes over and wholly incloses the member 16, the rods being disposed longitudinally in 65 the said member and the stop extending lat-

erally across the same, being so arranged as to not be engaged during the telescoping operation. As the bags suspended upon the rods 11, engage the stop arms 20 and 21 on the fixed member 16, the bags will be moved off of their supporting rods 11 and deposited in the casing 16. In a like manner the bags suspended by the rod 19 in the fixed member 16 will be deposited in the movable member 7. The bags may be withdrawn from their casings after the interchanging operation through the apertures 23 and through the doors 10.

It is obvious from the foregoing that I have provided an extremely simple and 80 thoroughly efficient means for effecting the interchange of mail pouches, and one which will prove highly practical in use. By employing an interchanging mechanism of this character, danger of damage to the bags is 85 greatly eliminated, and the interchange is effected without possibility of loss or dropping of the bags.

While the present disclosure is that of what is believed to be the preferred embodiment of the invention, it is to be understood that the invention is not limited thereto, but that various changes in the minor details of construction, proportion and arrangement of parts may be resorted to if desired without departing from the spirit of the invention as defined by the appended claims.

What is claimed is:

1. In a mail transferring device, a fixed tubular member, a pair of oppositely directed longitudinally disposed rods in said member adapted to support mail bags suspended therein, a stop arm in said member extending across the same between the adjacent ends of said rods, a movable tubular member of smaller diameter than the first mentioned member adapted to pass longitudinally over the latter, a pair of oppositely directed longitudinally disposed rods in said movable member adapted to hold 100 mail bags suspended therein, a stop arm extending across said movable member between the adjacent ends of the rods therein, and the rods and arms in said fixed and movable members being arranged so as to 105 not engage each other.

2. In a mail transferring device, a fixed tubular member slotted at one side throughout its length and open at both ends, a pair of oppositely disposed longitudinally extending rods in said member adapted to hold 110 mail bags suspended therein, a stop extending across said member between said rods; a movable tubular member slotted at one side throughout its length and being adapted to 115 pass longitudinally over said fixed member, a pair of oppositely disposed rods extending longitudinally in said movable member and being adapted to hold mail bags suspended therein, a stop extending across said 120

movable member between said rods, leaf springs engaged at the free ends with the outer ends of the rods in said movable member, and the said stops and rods in the fixed and movable members being arranged so as to pass without engaging each other.

3. In a bag holder, a tubular member open at both ends, a door in one side of said member, a rod secured at one end to the inner surface of said door adjacent one end thereof and extending longitudinally and in spaced parallel relation to the axis of said member, and a leaf spring engaged at its free end with the opposite end of said rod.
- 15 4. In a mail transferring device, the combination with a pair of tubular members open at both ends and one being adapted to pass longitudinally over the other, an arm

extending substantially diametrically across each tubular member intermediate the ends thereof, a pair of arcuate arms in each member above and below the straight arms therein, the arms carried by said members being adapted to pass each other when the said members are telescoped, and a longitudinally extending rod at the upper portion of one of said members and upon the interior thereof adapted to have mail bags suspended therefrom.

20 In testimony whereof I affix my signature 25 in presence of two witnesses.

CHARLEY W. ROBERSON.
